UNITED STATES PATENT OFFICE.

SOPHUS P. C. BORSON, OF SALIDA, COLORADO.

MINING-MACHINE.

1,203,573.

Specification of Letters Patent. Patented Nov. 7, 1916.

Application filed November 27, 1914. Serial No. 874,295.

To all whom it may concern:

Be it known that I, SOPHUS P. C. BORSON, a citizen of the United States, residing at Salida, in the county of Chaffee and State of Colorado, have invented a new and useful Mining Machine, of which the following is a specification.

My invention relates to a mining machine in which a revolving separating chamber 10 operates in conjunction with a vibrating concentrating chamber.

The separator hereinafter described is disclosed and claimed in my application for mining machine, Serial No. 814,462, filed 15 Jan. 26, 1914.

The objects of my invention are, first, to produce a machine which will handle large quantities of material at a low operating cost, thereby making it possible to concentrate 20 metalliferous ores and placer deposits too low in value to be profitably handled by any existing machine or process; second, to produce a machine which for its operation requires but a small quantity of water, thus 25 making it possible to concentrate placer deposits which owing to scarcity of water, cannot be handled profitably by any existing machine; and, third, to produce a machine light in weight, simple and positive 30 in operation, and particularly adapted to the requirements of placer mining in localities remote and difficult of access. I attain these 35 objects by means of the mechanism illustrated in the accompanying drawings, in 40 which:

Figure 1, is half elevation and half vertical section of the entire machine; Fig. 2, is a half horizontal section taken approximately on the line A—A, Fig. 1; Fig. 3, is 45 a vertical section of the concentrator alone taken approximately on the line B—B, Fig. 4; Fig. 4, is a horizontal section of the concentrator taken on the line C—C, Fig. 3; Fig. 5, is a vertical section of a modified 50 type of concentrator taken approximately on the line D—D, Fig. 6; Fig. 6, is a horizontal section of the concentrator taken approximately on the line E—E, Fig. 5; Fig. 7, is a horizontal section of a portion of the 55 machine on the line J—J, Fig. 1, showing one of the discharge vanes; Fig. 8, is a diagram illustrating the action of concentration in a concentrator having a polygonal cross-section; Fig. 9, is a diagram illustrating the action of concentration in a concentrator having a conical shell provided with

inwardly projecting ribs or flanges; Fig. 10, is a view in elevation of two complete machines; Fig. 11, is a vertical section of a modified type of concentrator having one 60 side depressed; Fig. 12, is an elevation of a connecting rod; Fig. 13, is a detail of one end of the connecting rod shown in Fig. 12; Fig. 14, is a plan view of the agitator piping; and Fig. 15, is a diagrammatic section through the step bearing and shaft with portions of the gate guides broken away, showing the gate as it would appear viewed from the bottom.

Similar characters refer to similar parts 70 throughout the several views.

Referring particularly to Figs. 1 and 2, a drive shaft 1, is rotatably mounted in a step bearing 2, and in a guide bearing 3, secured to external framework 4. Power to rotate 75 the drive shaft is transmitted through a pulley, rope sheave, sprocket wheel, spur or bevel gear 5, rigidly mounted on drive shaft 1. A feed hopper 6, having a conical shell or casing, open at top and bottom, is 80 suspended near the top of the drive shaft, and supported in any convenient manner; in the method indicated in the drawings, lugs or brackets 7, are rigidly secured to the feed hopper casing 6, and bolted to beams or 85 girders 8, of an external framework. The separating chamber, or separator, comprises a casing 9, circular or polygonal in cross-section, terminating above in a peripheral or 90 polygonal flange 10, and below in a central hub 11, and a screen, grizzly, or perforated plate 13, suspended above the bowl 9, and secured in place in any convenient manner; in the method indicated in the drawings the screen is secured at its upper periphery to 95 the flange 16, and at its lower periphery in a recess or groove 14, in hub 11. The separator is surrounded by a guide chamber, which consists of a shell or casing 15, circular or polygonal in cross-section, terminating above in a peripheral or polygonal flange 16, and below in a converging apron 17. The guide casing is rigidly secured to the 100 separator casing in any convenient manner; in the method indicated in the drawings the two casings are connected above by a plurality of lugs 18, and below by a plurality of brackets or arms 19. The separator hub 11, is rigidly secured to the drive shaft 1, in any convenient manner, as by means of a key, setscrews, screwthreads, or any combination thereof; hence both chambers revolve 105

with the drive shaft as one integral structure. The concentrating chamber, or concentrator, consists of a shell or casing 20, cylindrical or polygonal in cross-section, terminating above in a peripheral or polygonal flange 21, and below in a central hub 22. An upwardly projecting sleeve 24, circular in cross-section, terminates in a guide bearing 25, in which the drive shaft 1, is journaled, and forms the lower face 26, of a thrust bearing of which the separator hub 11, forms the upper face; a circular flange or lip 12, projecting from hub 11, forms the external wall of the said bearing. The thrust bearing for the concentrating chamber is formed by the lower face of hub 22, the upper face of step bearing 2, and the circular flange or lip 23, projecting from hub 22. Circular thrust disks 41, and thrust collars 42, or ball bearing 43, (Fig. 3), may be provided in the thrust bearings to reduce friction.

An operating arm or lever 27, provided with a hole 28, projects from one side of hub 22, to which it is rigidly secured. This arm serves to vibrate the concentrating receptacle about the drive shaft 1, through an angle of less than 180 degrees. Power to vibrate the concentrator is delivered to the operating arm 27, in any convenient manner; in the method indicated in the drawings a bolt or pin 29, joins the operating arm 27, to the jaw 30, of a reciprocating connecting rod 31, (Figs. 4, 12 and 13); the jaw 30, is preferably provided with a slotted hole 32, for the pin 29, to vibrate in, and with a shock absorbing or shock reducing medium, as, for instance, rubber blocks or cushions 66. The drawing 40 shows the connecting rod 31, bolted to an eccentric, but the objects of my invention may be accomplished equally well if, instead of the eccentric, a crank pin is journaled in one end of the connecting rod.

45 A discharge outlet formed by one or more rectangular, elliptical, or oval slots or holes 33, is provided in the bottom of the concentrating chamber, preferably at the angle formed by the intersection of the bottom and side of the bowl or casing 20, diametrically opposite the operating arm 27, as shown in the drawings. An outlet gate 34, provided with one or more rectangular, elliptical, or oval slots or holes 35, adapted to register with outlet passages 33, is slidably mounted in any convenient manner on the concentrator casing 20. In the method shown in the drawings a gate seat is formed on one side by a recess or groove 37, in hub 22, and on the other side by a grooved guide 38, secured to concentrator casing 20, by means of rivets or bolts. Pins or stops 39 and 40, secured to the bottom of concentrator casing 20, serve to limit the movement of the gate 34; the outlet being open

or uncovered when the gate 34, is brought to bear against stop 39; and closed when the gate 34, is brought against stop 40, as shown in Figs. 2 and 15. Gate operating means are furnished by slots or projections 36, shown in outline near the ends of gate 34.

In connection with the outlet and gate the following points are to be noted: 1. The number of slotted holes 35, in the gate 34, equals the number of passages 33, in the outlet. 2. In the closed position of the gate 34, the webs connecting and surrounding the holes 35, completely cover the passages 33, forming watertight joints. 3. In the open position of the gate 34, the holes 35, register with the passages 33, and permit the free discharge of concentrates or other matter from within the concentrator casing 20. 4. The gate 34, may be opened or closed at will, while the concentrator is in motion or at rest.

Figs. 3 and 4, show a modified design embodying my invention. Here the separator unit has been omitted, and the concentrator unit is designed to receive screened or sized material from a screening device or other proper source of supply, terminating preferably in a spout or chute 65. A modified guide chamber is shown, having the peripheral or polygonal flange 16, the apron 17, and the arms or brackets 19, rigidly connecting and securing the apron 17, to the central hub 11. The concentrator contains all the features previously described in connection with the concentrator shown in Figs. 1 and 2, but owing to the absence of mechanical agitators, to be hereinafter described, the bottom may be made to slope toward the discharge outlet from a point 53, diametrically opposite.

Figs. 5 and 6, show another modified design embodying my invention. Here a drive shaft 1', is rotatably mounted in a step bearing 2', and in a guide bearing 3, secured to external framework 4. A feed hopper 6, is suspended above and within the concentrator, and supported by means of lugs 7, rigidly secured to casing 6, and to the external framework 8. For the sake of clearness of illustration the lugs 7, as they appear in Fig. 6, have been rotated through a horizontal angle of 45 degrees from their position in Fig. 5. The concentrator contains the casing 20, flange 21, hub 22, operating arm or lever 27, and the discharge outlet and gate detail described in connection with Figs. 1 and 2. The hub extension 24, is carried up on the drive shaft sufficiently to insure stiffness and rigidity, and the hub 22, is rigidly mounted on the drive shaft 1', forming a watertight joint with same. This joint may be made by means of a key, setscrews, screwthreads, or any combination thereof, or the drive

shaft 1', may be cast into the concentrator hub 22, in the foundry. Power may be delivered through the operating arm or lever 27, in the manner hereinbefore explained; or the latter may be omitted and replaced by an operating crank 64, shown dotted, rigidly attached to the drive shaft near the top.

The tailings or waste material may be discharged by gravity by simply erecting the machine with its axis inclined from the vertical, as shown in Figs. 1 and 3, thus causing the tailings to overflow over the lower side; but to facilitate the discharge of tailings or waste material, I prefer to add some positive mechanical discharging device to the machine.

One type of mechanical discharger forming a part of my invention is shown in Figs. 1, 3, 4 and 7; it consists of one or more scoop-like vanes 44, rigidly mounted on the guide casing 17, and revolving with the same. In Figs. 3 and 4, the discharge vanes are shown cast on the apron 17, while in Figs. 1 and 7, they are shown riveted or bolted on the apron 17; the latter method is considered preferable since it permits the vanes to be removed and replaced when worn. Two discharge vanes are shown in the drawings, but the purpose of my invention may be accomplished equally well by using any convenient number of vanes greater or less than two. Another type of discharger, forming a part of my invention, is shown in Figs. 5 and 6; it consists of a discharger 54, having inlets 55 and 56, outlet 57, a central web or partition 58, enlarged to form a hub 59, provided with a central hole 60. The discharger is supported by a collar 62, on a shaft 61, and is free to slide or rise vertically on said shaft 61, but prevented from rotating about the latter by a key 63. The discharge vanes 44, are best adapted to be used in connection with a machine erected with its axis of vibration inclined from the vertical, as shown in Figs. 1 and 3, while the discharger 54, is best adapted to be used on a machine erected with its axis of vibration vertical; but the objects of my invention may be accomplished equally well by using the discharger 54, in connection with a machine erected with an inclined axis of vibration. The vanes 44, may also be used in a machine erected with a vertical axis, by constructing the concentrator with the casing 20, and flange 21, lowered or depressed on the side where the discharge is desired. This construction is shown in Fig. 11.

To prevent detrimental action due to deposits of sediment on the bottom of the concentrator, particularly after the latter has been at rest, I find it necessary to stir or agitate the material in the lower part of the concentrator, while the latter is in motion.

A form of mechanical agitation embodying my invention is shown in Figs. 1 and 2; it consists of one or more metal bars 45, round, square, oval, or rectangular in cross-section, rigidly mounted on the apron 17, of the guide chamber, with their lower ends in close proximity to the bottom of the concentrator. The bars 45, are riveted or bolted on the apron 17, in such manner that they may readily be removed and replaced when worn. The rotation of the apron 17, and the attached agitating bars 45, causes a local agitation of the material near the bottom of the concentrator where such action is desirable, but leaves the upper strata undisturbed. Similar agitators 45, are shown in Figs. 5 and 6, rigidly mounted on the feed hopper 6. As the said feed hopper and agitators are stationary the agitating action is caused by the vibration of the concentrator casing 20.

In the drawing four agitating bars are shown, but the objects of my invention may be carried out equally well by using a greater or less number of agitating bars. In Figs. 3, 4 and 14, is shown another agitating device embodying my invention. It consists of a system of piping adapted to carry air, water, steam, gas, or any similar fluid, under a pressure higher than atmospheric. As the fluid escapes from a medium of higher to a medium of lower pressure it forces its way up through the material in the concentrator and by this action agitates said material. The said agitating fluid has a further beneficial action in that it subjects the various particles of material in the concentrator to upwardly acting forces, and thereby improves the process of concentration. The system consists of a flexible tube or hose 46, (Figs. 4 and 14), leading from a reservoir or other source of supply, inlet pipe 47, main supply pipe 48, branch supply pipes 49, distributing pipe 50, discharge pipes 51, and discharge outlets or nozzles 52, formed by holes through the casing 20. The drawings show two branch supply pipes 49, and four discharge pipes 51, but the purpose of my invention may be accomplished equally well by using a greater or less number of these pipes. The pipes are secured to the casing 20, by means of ordinary pipe clamps or straps and screws or bolts.

To avoid a multiplicity of views, all the different combinations of details which it is possible to form with the matter disclosed have not been shown separately in the drawings; but it is evident that without deviating from the principle of my invention I may combine in operative relation any element shown in one view with the corresponding element or elements shown in another view, as for instance: the concentrators shown in Figs. 1, 2, 3, and 4, may be equipped with the discharging device 54, instead of the dis-

- charge vanes 44; the concentrators shown in Figs. 1, 2, 5 and 6, may be equipped with fluid agitating means instead of mechanical agitators; the concentrators shown in Figs. 5, 1, 2, 5 and 6, may be constructed with sloping instead of straight bottom; the machines shown in Figs. 1, 2, 3 and 4, may be erected with vertical instead of inclined axis of rotation; the concentrator shown in Figs. 3 and 4, may be equipped with mechanical instead of fluid agitating means; and the concentrator shown in Figs. 3 and 4, may be constructed with straight instead of inclined bottom.
- 15 In operation the mixture of fine and coarse material and water is delivered by the feed hopper into the bottom of the screening device near the center of the same, the wall of the feed hopper protecting the incoming raw material from contact with the departing screened material. The water serves the double purpose of washing and freeing the oversize material from all fine concentrates, and of preventing clogging of the screening surface. By the centrifugal action developed by the rotation of the separator the oversize material is elevated and discharged over the periphery of the screening device while the mixture of fine material and water passes through the screen and enters the concentrator through the guide casing. The latter introduces the mixture of fine material and water into the bottom of the concentrator near the center of the same, the wall of the guide casing protecting the entering material from contact with the departing tailings and gangues. The oscillating motion of the concentrator, combined with the action of the agitating means, maintains the material in the concentrating receptacle in a state of fluidity and mobility, causing the concentrates to at once descend and the tailings and gangues to ascend.
- Referring particularly to Figs. 1 and 2, power is delivered at the pulley, gear, sprocket, or sheave 5, by means of a belt, gear, chain, or rope, not shown, and a revolving motion, in the direction of the arrow, Fig. 7, imparted to the drive shaft, separator, guide chamber, and agitators 45. At the same time a vibrating motion is imparted to the concentrator, by means of the operating arm 27. Gold-bearing or metalliferous materials or ores are delivered preferably in a continuous manner into the feed hopper 6, and by the latter distributed over the bottom of the separator. Water is also introduced into the feed hopper 6, through a water connection 67, leading from a source of supply. When the material, saturated with water, comes in contact with the revolving screen 13, it is whirled outward and upward by centrifugal force. Rock gravel and particles above a specified size are carried up over the screening surface, finally

discharging over the lowest point of the flange 16, into a hopper, tailings conveyer, or other arrangement provided for the disposal of oversize material, while the smaller particles, or fines, are washed through the said screen 13, and by centrifugal force carried along the interior surface of the casing 9, and up over the flange 10. Here the tendency of the said fines is to leave the separator at a tangent, but this is prevented by the wall 15, of the guide chamber. The particles of material are for a moment poised in space while their potential energy is being converted into kinetic energy, and then the particles of material, guided by the apron 17, are precipitated into the concentrator. During the latter operation a certain momentum is imparted to the particles of material the intensity of which is proportional to the respective specific gravities of the various particles; hence, the particles having the higher specific gravities are carried to a greater depth than those having lower specific gravities. The vibratory motion of the concentrator serves to separate the fines into strata whose positions above the bottom vary with their respective specific gravities. The concentrates having the higher specific gravity collect on the extreme bottom of the concentrating chamber, and as the lowest point of the latter communicates directly with the outlet passages 33, the concentrates may be drawn off continuously or intermittently by opening the outlet gate 34. The tailings, or particles having the lower specific gravities, gradually ascend in the concentrating receptacle, partly by the centrifugal impulses imparted to them by the motion of the latter, and partly by being displaced by the incoming material; hence the said tailings are discharged in a continuous series of impulses over the flange 21, into a hopper, tailings conveyer, or other arrangement provided for the discharge of tailings.

Under ordinary conditions the machine will be erected with its drive shaft and the axis of rotation of its chambers inclined from the vertical at an angle sufficiently great to effect the discharge of tailings in the manner just described, but the displacement and discharge of tailings may be greatly accelerated by the addition of the discharge vanes 44, and it is therefore my intention, under ordinary conditions, to equip my machine with one or more of these discharge vanes. Referring to Fig. 1, the horizontal line F—F, represents the level at which the oversize material is discharged over the flange 16, of the separating chamber; the horizontal line H—H, represents the water level in the separator casing 9, and also the level at which the fines passing through the screening device are discharged into the guide chamber; and the horizontal

line J—J, indicates the level at which the tailings are discharged over the flange 21, of the concentrator casing; the line J—J, may coincide with the water level in chamber 20, 5 or the latter may be slightly lower. One discharge vane 44, is shown submerged, and the other above the surface of the material. After a rotation of 90 degrees in the direction of the arrow, Fig. 7, one vane will be 10 at the point of leaving and the other at the point of entering the material. Under certain conditions, as for instance when dealing with concentrates of comparatively low specific gravity, it is preferable to erect the 15 machine with its drive shaft and its axis of vibration vertical, or nearly vertical; and in order to insure the discharge of tailings at a given point on the periphery, it becomes necessary to construct the concentrator with 20 the casing 20, and flange 21, depressed on the discharge side, as shown in Fig. 11, or to equip the machine with a discharger of the type shown in Figs. 5 and 6. The vibrating motion of the concentrator produces 25 powerful centrifugal impulses in the therein contained tailings. An impulse in the direction of the clockwise arrow, Fig. 6, hurls the tailings into the discharge inlet 55, whence it is deflected by the rib 58, into 30 the discharge outlet 57, while an impulse in the direction of the anti-clockwise arrow, forces the tailings into the discharge inlet 56, against the rib 58, and into discharge outlet 57. Normally the vibrating impulses 35 are delivered sufficiently rapidly to produce a nearly uniform flow of tailings from the discharger outlet.

When the concentrator is constructed without the separator, as shown in Figs. 3 40 and 5, the material for concentration is received screened or sized from an external source terminating in the spout or chute 65, and delivered into the guide chamber 17, Fig. 3, or the feed hopper 6, Fig. 5; water 45 is delivered through the connection 67; and the process of concentration from this point is identical with that just described.

A detailed description of the process of concentration on which my invention is 50 based, and a statement of the considerations governing the design of the machine for different classes of material follow: Let it be assumed that the concentrator is partly or wholly filled with a saturated or semi- 55 liquid mixture of material to be concentrated, and that the concentrator is set in motion and vibrated through a horizontal angle of less than 180 degrees. For the purpose of illustration the machine is assumed 60 to be divided into four types.

Type 1: Figs. 5 and 6, show a concentrator having a circular cross-section, and erected with its axis of vibration vertical. Theoretically, a particle of matter entering 65 the concentrator will tend to fly off at a

tangent until restrained by the casing 20. Each vibration of the concentrator produces a corresponding motion of the particle, causing the latter to move in a path forming an arc of a circle. A particle of matter having 70 a high specific gravity will describe a descending series of circular arcs, with constantly decreasing radii; while a particle of matter having a low specific gravity will describe an ascending series of circular arcs, 75 with constantly increasing radii. Actually, the particle will collide with other particles, and its path will be more or less erratic, but its tendency will be to describe circular arcs.

Type 2: The concentrator casing shown 80 in Figs. 1, 2, 3, and 4, is identical in construction with that described under Type 1, but is erected with its axis of vibration inclined from the vertical. Theoretically, a particle of matter entering the concentrator 85 tends to fly off at a tangent until restrained by casing 20. Each vibration of the concentrator causes the particle to move in a parabolic path, owing to the constantly varying radius of vibration in any given 90 horizontal plane, due to the inclination of the axis of vibration. A particle of matter having a high specific gravity will describe a descending series of parabolas; while a particle of matter having a low specific 95 gravity will describe an ascending series of parabolas. Actually, the effect produced by a great number of particles moving in intersecting parabolic paths is in the nature of a tremor in each horizontal stratum, which 100 effect is intensified by collisions of the particles.

Type 3: In Fig. 8, is shown, in outline, a concentrator having a polygonal cross-section. An octagonal casing is shown, but in 105 actual construction the concentrator may have any convenient number of sides greater or less than eight. A particle of matter starting at the point *a*, Fig. 8, will move to the point *b*, in a path similar to that indicated by the dotted curve 69. The path in any horizontal plane follows the general direction of a circular arc composed of a number of reverse curves; that is, a curve plotted through the center of gravity of 110 each element of the dotted curve 69, Fig. 8, would be a circle. The reverse curves are produced by the constantly changing radius of vibration; said radius being maximum 115 at the angles, and minimum at the sides 120 of the casing 20. The ascending and descending paths are governed by the laws stated in connection with Types 1 and 2.

Type 4: If the concentrator shown in 125 outline in Fig. 8, is assumed to be erected with its axis of vibration inclined from the vertical, a particle of matter will move in a path represented by a number of connecting reverse curves; but a line plotted through the center of gravity of each ele-

ment of the dotted curve, from *a* to *b*, Fig. 8, would be a parabola.

Fig. 9, shows in outline a horizontal section of a concentrator having a casing similar to that shown in Figs. 2, 4 and 6, but provided with a plurality of ribs or flanges 68, rigidly secured to the casing 20. The object of these ribs or flanges is to cause a variation in the radius of vibration, and to produce a motion within the concentrator similar to that described under Type 3, when the machine shown in Fig. 9, is erected with a vertical axis of vibration; and similar to that described under Type 4, when the machine shown in Fig. 9, is erected with an inclined axis of vibration.

A comparison of the types of concentrator just described discloses the fact that the four types produce concentrating motions varying from gentle to intense. Type 1, for instance, is particularly adapted to the concentration of relatively non-cohesive materials of comparatively low specific gravity; Type 2, to relatively non-cohesive materials of higher specific gravity; Type 3, to relatively cohesive materials of comparatively low specific gravity; and Type 4, to relatively cohesive materials of higher specific gravity. It will thus be evident that although the principle underlying my invention does not in any case vary, the actual design and construction of the machine is subject to variation and modification to meet working conditions. The same is true of the agitators; experience has convinced me that agitation of the lower strata is necessary. In localities where a fluid under pressure, such as air, water, gas, etc., is available the machine may be designed and equipped with a system of fluid agitation, while in localities where such agitating fluid is not economically obtainable, the machine will preferably be designed and equipped with mechanical agitators. Under certain conditions the concentrator may be equipped with both systems of agitation.

To obtain capacity in excess of the capacity of a single machine, I propose to operate two or more machines in battery. This is shown in Fig. 10, where two machines are erected on a platform 74, and supported by the structure 75. Power is delivered to the two separators by the countershaft 76, and to the two concentrators by the line shaft 77, operatively connected to shaft 76, by a belt 78. A feeder 69, provided with discharge chutes and means for controlling and regulating the discharge therefrom, receives raw material from an external source and discharges the same into the feed hoppers 6. Oversize material is discharged from the separators into the hopper 71, and tailings are discharged from the concentrators into the hopper 72. Hoppers 71 and 72, communicate, and the lower sec-

tion 73, of hopper 72, contains, or communicates with, a tailings conveyer or similar device for the removal of tailings and oversize material. The removal of concentrates is preferably effected by having the concentrators discharge into amalgamating or similar devices 70. Where no gravity supply of water is available a pump 68, provided with suction 79, and discharge 80, furnishes water to the feeders through valve-regulated nozzles on the conduit 67, and to the fluid agitators through valve-regulated conduits 81, connecting with the flexible conduit 46, (Fig. 14). When the machine is used for cyaniding or similar processes the pulp passes from the feeders 6, to the screens, the oversizes flowing into the hopper 71, and to apparatus for regrinding; the fines pass through the guide chambers, and into the concentrators, the slimes flowing into the hopper 72, and from there to slime tanks, while the concentrates are discharged into the apparatus 70. The arrangement shown in Fig. 10, also serves to illustrate the erection, in multiple, of the concentrator shown in Figs. 3 and 4. The hoppers 6 and 71, would be omitted; the feeder 69, would discharge directly into the guide chambers 17, of the concentrators, and the machine would be erected and operated in the manner above described.

Having described my invention I claim:

1. In combination, a guide casing mounted for rotation upon an inclined axis, a concentrating receptacle mounted upon an inclined axis below and concentric with said guide casing and adapted to receive material for concentration therefrom, said concentrating receptacle partly inclosing said guide casing, means attached to said guide casing adapted to elevate and discharge tailings and gangues from said concentrating receptacle, means for rotating said guide casing about its axis, and means for oscillating said concentrating receptacle about its axis, substantially as shown and described.

2. In combination, a guide casing mounted for rotation upon an inclined axis, a concentrating receptacle mounted upon an inclined axis below and concentric with said guide casing and adapted to receive material for concentration therefrom, said concentrating receptacle partly inclosing said guide casing, means attached to said guide casing adapted to elevate and discharge tailings and gangues from said concentrating receptacle, controllable means for discharging concentrates at the bottom of said concentrating receptacle, means for rotating said guide casing about its axis, and means for oscillating said concentrating receptacle about its axis, substantially as shown and described.

3. In combination, a guide casing mounted for rotation upon an inclined axis, a con-

- centrating receptacle mounted upon an inclined axis below and concentric with said guide casing and adapted to receive material for concentration therefrom, said concentrating receptacle partly inclosing said guide casing, means attached to said guide casing adapted to elevate and discharge tailings and gangues from said concentrating receptacle, controllable means for discharging concentrates at the bottom of said concentrating receptacle, agitating means to prevent the formation of sediment in said concentrating receptacle, means for rotating said guide casing about its axis, and means for oscillating said concentrating receptacle about its axis, substantially as shown and described.
4. In combination, a concentrating receptacle open at the top and converging from top to bottom mounted upon an inclined axis, said receptacle having its bottom pierced to form a plurality of concentrates discharge outlets, controllable means for covering and uncovering said discharge outlets, a guide casing mounted for rotation upon an inclined axis within and partly above said concentrating receptacle, said guide casing being adapted to discharge material for concentration centrally above the bottom of said concentrating receptacle in a manner to prevent contact between entering unconcentrated material and departing treated material, means attached to said guide casing adapted to elevate and discharge tailings and gangues from said concentrating receptacle, means for rotating said guide casing about its axis, and means for vibrating said concentrating receptacle about its axis, substantially as shown and described.
5. In combination, a concentrating receptacle open at the top and converging from top to bottom mounted upon an inclined axis, said receptacle having its bottom pierced to form a plurality of concentrates discharge outlets, controllable means for covering and uncovering said discharge outlets, a guide casing mounted for rotation upon an inclined axis within and partly above said concentrating receptacle, said guide casing being adapted to discharge material for concentration centrally above the bottom of said concentrating receptacle in a manner to prevent contact between entering unconcentrated material and departing treated material, flanged vanes attached to and rotatable with said guide casing and adapted to elevate and discharge tailings and gangues from said concentrating receptacle, means for rotating said guide casing about its axis, agitating means to prevent the formation of sediment in said concentrating receptacle, and means for oscillating said concentrating receptacle about its axis, substantially as shown and described.
6. In combination, a concentrating receptacle open at the top and converging from top to bottom mounted upon an inclined axis, said receptacle being apertured to form a plurality of concentrates discharge outlets, controllable means for covering and uncovering said discharge outlets, a guide casing mounted for rotation upon an inclined axis within and partly above said concentrating receptacle, said guide casing being adapted to discharge material for concentration centrally above the bottom of said concentrating receptacle in a manner to prevent contact between descending unconcentrated material and ascending treated material, scoops attached to and rotatable with said guide casing and adapted to elevate and discharge tailings and gangues from said concentrating receptacle, means for rotating said guide casing about its axis, agitating means to prevent the formation of sediment in said concentrating receptacle, and means for oscillating said concentrating receptacle about its axis, substantially as shown and described.
7. In combination, a concentrating receptacle converging from top to bottom mounted for oscillation upon an inclined axis, a guide casing mounted upon an inclined axis above and partly within said concentrating receptacle and concentric therewith, said guide casing being adapted to discharge material for concentration centrally above the bottom of said concentrating receptacle but below the discharge level of the tailings and gangues therein, controllable means for discharging concentrates from the bottom of said receptacle, and means for vibrating said concentrating receptacle about its axis, substantially as shown and described.
8. In combination, a concentrating receptacle converging from top to bottom mounted for oscillation upon an inclined axis, a guide casing mounted above and partly within said concentrating receptacle concentric therewith and upon an inclined axis, said guide casing being adapted to discharge material for concentration centrally above the bottom of said concentrating receptacle but below the discharge level of the tailings and gangues therein, controllable means for discharging concentrates from the bottom of said receptacle, agitating means to prevent the formation of sediment in said concentrating receptacle, and means for vibrating said concentrating receptacle about its axis, substantially as shown and described.
9. In combination, a sizing means mounted for rotation upon an inclined axis, a guide casing attached to and rotatable with said sizing means, a concentrating receptacle mounted concentric with said sizing means and its guide casing and upon an inclined axis, said receptacle partly inclosing said guide casing, means for oscillating said con-

centrating receptacle about its axis, and means attached to said guide casing adapted to elevate and discharge tailings and gangues from said concentrating receptacle, substantially as shown and described.

10. In combination, a sizing means mounted for rotation upon an inclined axis, a concentrating receptacle mounted concentric with said sizing means and upon an inclined axis, a guide casing attached to and rotatable with said sizing means and adapted to transfer material for concentration from said sizing means into said concentrating receptacle, means attached to said guide casing adapted to elevate and discharge tailings and gangues from said concentrating receptacle, means for rotating said sizing means and guide casing about their axis, and means for oscillating said concentrating receptacle about its axis, substantially as shown and described.

11. In combination, a sizing means mounted for rotation upon an inclined axis, a guide casing attached to and rotatable with said sizing means, a concentrating receptacle mounted concentric with said sizing means and its guide casing and upon an inclined axis, said receptacle partly inclosing said guide casing, means for oscillating said concentrating receptacle about its axis, means for rotating said sizing means and guide casing about their common axis, means attached to said guide casing adapted to elevate and discharge tailings and gangues from said concentrating receptacle, and controllable means for discharging concentrates at the bottom of the concentrating receptacle, substantially as shown and described.

12. In combination, a sizing means mounted for rotation upon an inclined axis, a guide casing attached to and rotatable with said sizing means, a concentrating receptacle mounted concentric with said sizing means and its guide casing and upon an inclined axis, said receptacle partly inclosing said guide casing, means for oscillating said concentrating receptacle about its axis, means for rotating said sizing means and guide

casing about their common axis, means attached to the said guide casing adapted to 50 elevate and discharge tailings and gangues from said concentrating receptacle, controllable means for discharging concentrates at the bottom of said concentrating receptacle, and agitating means to prevent the 55 formation of sediment in said concentrating receptacle, substantially as shown and described.

13. In combination, a concentrating receptacle mounted for oscillation upon an inclined axis and having its bottom pierced to form a plurality of concentrates discharge outlets, a guide casing mounted concentrically above and partly within said concentrating receptacle and upon an inclined axis, 65 said guide casing being adapted to deliver into said concentrating receptacle, a sizing means mounted for rotation upon an inclined axis concentrically within said guide casing and attached thereto, said sizing 70 means being constructed to wash and dissociate coarse and fine material, a feed hopper mounted upon an inclined axis above and partly within said sizing means and adapted to deliver water and material for 75 separation thereinto, means attached to said guide casing adapted to elevate and discharge tailings and gangues from said concentrating receptacle, controllable means for discharging concentrates at the bottom of 80 said concentrating receptacle, agitating means to prevent the formation of sediment in said concentrating receptacle, means for rotating said sizing means and guide casing about their common axis, and means for oscillating said concentrating receptacle about 85 its axis, substantially as shown and described.

In testimony whereof I have signed my name in the presence of two subscribing witnesses.

SOPHUS P. C. BORSON.
